UNITED STATES PATENT OFFICE.

RICHARD BIRKHOLZ, OF MILWAUKEE, WISCONSIN, ASSIGNOR TO EDWARD P. ALLIS, OF SAME PLACE.

SPIRAL CONVEYER.

SPECIFICATION forming part of Letters Patent No. 355,124, dated December 28, 1886.

Application filed October 4, 1886. Serial No. 215,281. (No model.)

To all whom it may concern:

Be it known that I, RICHARD BIRKHOLZ, of Milwaukee, in the county of Milwaukee and State of Wisconsin, have invented certain new 5 and useful Improvements in Spiral Conveyers, of which the following is a specification.

My invention relates to spiral conveyers, and has for its object to construct a conveyer so that its flights may be removed from the 10 shaft and reversed, whereby the conveyer may be made a "right" or "left" conveyer, at will.

In milling machinery and in other classes of machinery it is often found necessary or desirable to change the throw or direction of feed 15 of the conveyer, so as to make the conveyer feed to the right or to the left, and at the same time to so construct the conveyer that this result may be accomplished without any change in the direction of rotation, because it is frequently impossible or undesirable to change 20 the direction of rotation of the shaft; and to produce such a conveyer is the object of my invention.

I desire to state that prior to my invention 25 various contrivances and plans have been devised in which the flights were secured directly but adjustably to the shaft, and that I am aware that it has been proposed to pivot the flights upon a shaft and to tip and rock 30 them to vary or change the inclination of the flights; and these features I disclaim.

My invention consists in providing the conveyer-shaft with hubs or collars to encircle the shaft, and secured thereto by means of a set- 35 screw or equivalent means, each collar or hub being provided with a single flight and adapted to be taken from the shaft when desired, reversed, and then placed thereon again and secured in place. By this means I produce a 40 conveyer that can be easily and quickly transformed from a right to a left conveyer, or vice versa.

In the drawings, Figure 1 is a side view of a portion of a conveyer-shaft with one flight in 45 position; Fig. 2, an end view of same; Fig. 3, a top view; Fig. 4, a face view of the flight; Fig. 5, a view showing the conveyer-flight transposed in position; Figs. 6 to 9, views illustrating a slight modification of construction 50 shown in Fig. 1. Figs. 10 to 13, 14 to 16, 17

to 20, and 21 to 25 are views illustrating in groups various modifications in the construction of the hub, the hub-securing, and the flight-attaching devices.

A indicates a shaft, which may be of wood 55 or iron, solid or hollow, and of any desired form in cross-section, the circular solid form being shown in the drawings, as such is most commonly used.

B indicates a hub or collar, which will be 60 preferably made of cast metal and of a size to fit the shaft, though this latter requirement is not essential, the hub or collar comprising under all the various constructions one, and in most cases two parts or halves, B' B², to one of or 65 between which the conveyer-flight C is secured. The manner of constructing this hub or collar is preferably as follows: I cast the parts B' and B² in one piece and with a hole through them to receive the shaft, or the hole may be 70 bored to fit. On opposite sides of the collar are cast integral therewith pins D, which project lengthwise thereof, as shown in Figs. 1 and 3. The casting thus constructed is cut diagonally in two in a vertical plane at an 75 oblique angle to the shaft, thus dividing the collar into halves B' and B², in all respects alike. Either half, B' or B², will be found to have a pin, D, and is provided with a set-screw, a, by which to secure the collar upon the shaft. 80 It is apparent that the two parts B' B² may be cast separately.

Referring now to Figs. 1 to 5, inclusive, I will describe the construction of the preferred form of conveyer. The hubs or collars B' B² are each 85 secured upon the shaft by means of a set-screw, a, and these hubs clamp between their adjacent faces the flight C, which latter is or may be of sheet metal and semi-elliptical in form. One of the pins D, formed upon each hub, enters a 90 hole in the flight, as shown in Figs. 1 and 3, and prevents any movement of the flight independent of the hub.

The flight shown in Figs. 1 to 5 is semi-elliptical, but owing to the inclination of the 95 same appears to be semicircular when looking at the end of the shaft, as in Figs. 2, 7, 11, 16, 18, and 22. The flight is cut out at its inner edge to fit upon the shaft, and is perforated to receive the pin D, and when thus constructed 100

it is placed between the adjacent faces of the two parts of the hub, as shown in Figs. 1, 3, and 5. When the flight is in position, the pin D projects through the hole and prevents 5 turning independently of the collar in case the flight should not be clamped tight enough between the collars.

When it is desired to reverse the conveyer, it is only necessary to loosen the nuts a and 10 slip the collars off the shaft, and after reversing the flight with its hub, end for end, slip it upon the shaft, as shown in Fig. 5.

It will be noticed that in Figs. 1, 2 and 3 15 while in the construction shown in Figs. 6 to 9, inclusive, one pin is formed on each of the halves of the hub.

In Figs. 10, 11, 12, and 13, instead of using 20 separate set-screws a and the pin D, I show perforated ears or lugs a² on each half of the hub, and a bolt, a³, passing through these lugs and through the conveyer-flight, this bolt not only serving to clamp the flight between the hub-sections B' B², but also serving 25 the same purpose as the pins D of the construction above explained. By reason of the inclination of the faces of the hubs between which the flight is clamped when the bolt a³ is drawn up tight, it causes the portions B' B² 30 to assume a position upon the shaft slightly at an angle thereto, and thus cramp or bind the collars upon the shaft.

In Figs. 14, 15, and 16 the hubs or collars are represented as beveled at the ends, as well 35 as being divided obliquely, each half B' B² being provided with its set-screw a and two pins, D. By beveling or inclining the ends of the hub I am enabled to bring the edges of the flights close together, should it be desired to 40 do so.

In Figs. 17 to 20, inclusive, is shown an arrangement by which only one-half of the hub B' is used, the flight being in such case secured to the inclined faces or end of the hub 45 by means of a bolt or screw, a⁴. The hub is retained upon the shaft by means of a set-screw, a, as shown, or equivalent means.

Figs. 21 to 25, inclusive, show a similar con-

struction. In this arrangement I employ one half, B', of the hub, but make this half in two parts, as shown, whereby the flight is not only secured in place between the parts of the hub, but the latter is secured in place upon the shaft. The flight is provided with two depending arms, a⁵, which are bent at right angles 55 to its body, as shown in dotted lines in Fig. 21.

These bent arms are placed between the two parts of the hub, and clamped therein by means of screws a⁶, which serve also to bind the two parts of the collar or hub upon the 60 shaft.

I consider that all the various forms herein described and shown are within the scope of my invention; but do not limit myself to any particular form of device. 65

Having thus described my invention, what I claim is—

1. In combination with a shaft, a hub or collar encircling the same and provided with a face oblique to the axis of the shaft, a flight secured to said oblique face, and means for securing the collar in position upon the shaft. 70

2. In combination with a shaft, a hub or collar encircling the same and consisting of two parts, B' and B², a flight secured between 75 the adjacent faces of the hub-sections, and a screw (one or more) for securing the flight to the collar and the collar upon the shaft.

3. In combination with a shaft, a hub or collar encircling the same, consisting of two 80 parts, B' and B², a pin, D, formed upon one of said parts and passing through the flight, and a set-screw, a, for securing the collar in place.

4. In combination with a shaft, a hub consisting of two parts and a flight secured to and 85 carried by said hub.

5. In combination with a shaft, a reversible removable hub or collar encircling the same and provided with a face oblique to the axis of the shaft, a flight secured to said oblique 90 face, and means for securing the collar in position upon the shaft.

RICHARD BIRKHOLZ.
